UNITED STATES PATENT OFFICE.

GEORGE PARKER, OF BAY CITY, MICHIGAN.

AUTOMATIC STOP FOR STEAM-ENGINES.

SPECIFICATION forming part of Letters Patent No. 337,611, dated March 9, 1886.

Application filed July 23, 1885. Serial No. 172,395. (No model.)

To all whom it may concern:

Be it known that I, GEORGE PARKER, of Bay City, in the county of Bay and State of Michigan, have invented new and useful Improvements in Automatic Stops for Steam-Engines; and I do hereby declare that the following is a full, clear, and exact description thereof, reference being had to the accompanying drawing which forms a part of this specification.

10 This invention relates to a new and useful improvement in stop-motion for steam-engines, of which the following is a specification, reference being had to the accompanying drawing, wherein my improvement is shown in elevation.

15 My stop-motion is designed to come automatically into action if the motion of the engine should increase beyond the limit of its normal action; and the object is to prevent the 20 engine from running away and thereby occasioning loss by breakage and otherwise, as often happens through the failure of the governor to act.

25 My invention consists in providing the throttle-valve of the engine with a tripping device so arranged that a detent, which is controlled by centrifugal force derived from the motion of the engine, will automatically trip it if the engine increases its motion beyond its normal 30 limit, all as hereinafter described.

35 A is the crank-shaft of the engine, and B is a flanged disk, preferably made in halves and bolted together, so as to be firmly secured to the crank-shaft.

40 C is a flying weight adjustably secured upon the arm D, which latter is pivotally secured at a to the disk.

45 E is a coil-spring secured at one end to the arm D, and at the other to a lever, F. The lever F is pivotally secured at b to the disk, and is provided at the rear end with an adjusting-screw, c.

50 G is an upright secured in proximity to the flanged rim of the disk B.

55 H is a weighted bar loosely held in position by the guides d d', and is provided with an offset or shoulder, e, which, when engaged upon the edge of the guide d', prevents the weighted bar from dropping by its weight through the 60 guides d d'.

I is the throttle-valve of the engine. J is its actuating lock-lever, provided with a counter-weight, K, and an arm, L, for unlocking, all so arranged that by pulling on the free end of the arm L the lever J is unlocked, and, impelled by the gravity of the weight K, automatically turns off the steam.

65 M is a chain or rope connected at one end to the unlocking-arm L of the throttle-valve lever, and at the other to the upper end of the 60 bar H, suitable sheaves being used to support the chain on. The operating-lever of the steam-whistle N is also preferably connected to this chain.

In practice the parts are so arranged that 65 when the speed of the engine increases beyond its normal limit the centrifugal force of the flying weight C becomes so great that the end of the arm D is projected beyond the rim or flange of the disk B, (a suitable slot being 70 made in the rim for that purpose,) and, acting as a detent, it strikes in the revolution of the disk against the bar H, and pushes it sufficiently back to release its shoulder e from engagement upon the guide d', allowing it to 75 drop by its gravity, when, by reason of the connecting-chain M, the actuating-lever of the throttle-valve is likewise released and the steam thereby automatically turned off, while the 80 whistle is automatically set blowing.

85 The throttle-valve herein described is the one patented to me March 3, 1885, No. 313,365; but it is obvious that any throttle-valve may be made self-closing in a similar manner, and I therefore do not want to confine myself to this construction alone.

What I claim as my invention is—

1. In a speed-governor, as described, the combination, with the weighted lever C D, pivoted to and actuated from the main shaft of 90 an engine, of an adjustable elbow-lever and a spring connecting the two levers, so as to regulate the rate of speed at which the weighted lever shall operate, as set forth.

2. In a speed-governor, the combination, with 95 the throttle-valve, as described, a tripping device, and connections, of the weighted lever D, the lever F, spring E, and adjusting-screw c, as and for the purposes set forth.

3. In combination with the throttle-valve I, 100

arranged to be self-closing when tripped, the chain M, the suspended bar H, having shoulder e, the rest d', the arm D, controlled by the centrifugal force of the engine, and the 5 disk B, all arranged substantially as described.

4. The combination of the upright G, having guides d d', the weighted bar H, having shoulder e, the disk B, the arm D, having

flying weight C, and the coil-spring E, having adjusting devices, such as the lever F, and adjusting-screw c, all arranged substantially as described.

GEORGE PARKER.
